JOHN J. TEMPLE, OF NEW YORK, N. Y., ASSIGNOR TO VICTOR METAL PRODUCTS CORPORATION, OF BROOKLYN, NEW YORK, A CORPORATION OF NEW YORK

MACHINE FOR INSERTING CORKS INTO CAPS FOR COLLAPSIBLE TUBES

Application filed March 28, 1931. Serial No. 525,958.

This invention relates to machines for automatically inserting cork discs into caps for collapsible tubes, which caps are automatically fed to and discharged from the machine.

Sealing corks have heretofore been inserted into caps used as removable closures for collapsible tubes. The cork discs, however, have not been firmly attached to the cap. When the cap is removed by the user from its collapsible tube, the cork disc frequently adheres to the end of the tube neck, and must be removed manually before any part of the contents of the tube can be conveniently discharged. The result is that the disc is frequently lost, whereby the cap forms an insecure closure for the end of the tube and permits the contents to dry out.

My invention contemplates the provision of a machine and of a method for automatically feeding caps, for cutting out cork discs from a suitable strip, and for inserting and cementing the disc to the cap in such a manner that the disc adheres firmly to the cap at all times and cannot be lost. My invention further contemplates the provision of a suitable cement for cementing the disc to the cap, which cement is unattacked by moisture or by the contents of the collapsible tube, and which is of such nature that it cannot injure such contents or have any deleterious effect thereon.

The various objects of my invention will be clear from the description which follows, and from the drawings, in which

Fig. 1 is a top plan view of my improved machine.

Fig. 2 is an end view thereof.

Fig. 3 is a front view thereof.

Fig. 4 is a front view and partial vertical section of the machine on an enlarged scale, showing the position of the parts, ready for the forming of a cork disc and the insertion thereof into a cap.

Fig. 5 is a similar view of the same, showing the parts in the position wherein the disc has been inserted into the cap, and the corked cap is about to be discharged from the machine and replaced by another cap.

Fig. 6 is a vertical section of the lower end

of the cap chute and of the supporting means for the cap, showing the cap about to be delivered into cork receiving position.

Fig. 7 is a bottom plan view of the same, and

Fig. 8 is a top plan view of the cap delivering slide and of the passage provided for the discharge of the corked cap.

In that practical embodiment of my invention which I have illustrated by way of example, the machine may be mounted on a suitable stand as 10, and includes a pair of suitable spaced frames 11 and 12 supporting the various operative instrumentalities of the machine. The frames may be braced by transverse braces 13, serving also, as supporting means for certain of the parts.

The caps 16 are automatically fed into the proper position, one at a time, for the insertion of the cork discs thereinto, as by means of a suitable hopper, not shown, of a type well known in the art, and a suitable cap chute. The caps are fed from the hopper to the cap chute 14, being controlled in their movement along the chute by a suitable escapement mechanism later to be described.

At the same time, a suitable cork strip as 15 is fed to the machine from a roll not shown, discs of the proper size being sheared from said strip at the proper point for inserting the discs into the caps. During the movement of the strip 15, it is gummed on its under face by a coating of suitable cement such as silicate of soda, to cause the discs to adhere substantially permanently to the cap on their insertion into the cap under the proper pressure.

The cap chute 14 is provided with a suitable T-shaped groove 17, the caps being fed along the chute with the enlarged heads thereof arranged downwardly, and sliding in the wider portion of the T-slot 17. At its lower end, the cap chute 14 terminates in a pair of spaced cap supporting plates 18 and 19, spaced apart a distance less than the diameter of the head of the cap so that the cap is supported by said plates until the cap has been completely discharged from the chute. Reciprocating between said plates is the cap positioning slide 21, which is adjust-

ably secured to the slideable cap discharge plate 22, as by means of the screw 23 adjustable in the slot 24 of said plate. The adjusting screw 25, secured to the slide 21, 5 serves to adjust said slide relatively to the plate 22, and is locked in position by means of the lock nuts 26 engaging a suitable support 27. On the proper adjustment of the screw 25, the limit of the innermost movement of the slide 21 is so determined that the 10 cap is properly positioned in the extreme position of the slide toward the left, ready for the reception of the cork to be inserted thereinto.

15 To so position the cap, the left end of the slide as viewed in Figs. 4, 6 and 8 is provided with a suitable groove as 28 for the reception of the head of the cap, and is further provided with an extension support as 29 on 20 which the cap rests during the cork inserting operation.

Cooperating with the slide 21 for positioning the cap, is the aligning member or stop 30 provided with the properly shaped wall 25 31 for engaging the similarly shaped edge 32 of the cap. The upper part 34 of the wall is properly shaped to fit and engage the neck 33 of the cap, said walls aligning the cap coaxially of the opening 35 in the shearing 30 die 135.

In order to prevent undue wear on the die and on the aligning stop, the opening 35 is 35 lined with the hardened steel bearing 36 in which the disc inserting plunger 37 operates. Prior to the advance of the cap by the slide 21, the cap is halted near the lower ends of the plates 18 and 19 by the ends of the bent 40 springs 61, which are secured to the stop 30 as at 62.

45 For reciprocating the slide 21 to advance the cap into cork-receiving position, the discharge plate 22 carrying the slide, is reciprocated by means of the cam 38 mounted on the drive shaft 39 of the machine, and operating against the cam roller 40, pivoted as at 41 to a suitable bracket 42, which is secured to said discharge plate as by means of suitable screws or bolts 43.

It will be seen that as the shaft 39 is 50 rotated, as by means of the pulley 139 thereon, the cam 38 operates upon the cam roller 40 to move said roller toward the right at the proper time, and to reciprocate the discharge plate 22 together with the slide 21 in the same 55 direction. The projection or support 29 is thereby withdrawn from underneath the bottom of the cap, to release the cap. The discharge opening 44 in the discharge plate is also brought into position beneath the cap 60 to allow the cap to drop therethrough by gravity after the cork disc has been inserted thereinto. Retrogression of the cap with the slide is prevented by the bent ends of the springs 61.

65 Return movement of the discharge plate

and of the slide connected thereto toward the left is effected by means of the springs 45 fastened at one end to the cross bar 46 of the discharge plate 22, and at their other ends to stationary pins as 47, said springs serving to maintain the roller 40 in pressed contact with the cam 38 and serving further to operate the slide 21 at the proper time to forward a cap discharged from the chute into cork-receiving 70 position.

75 As will be clear from Figs. 6, 7 and 8, the edge 48 of the slide 21 is suitably shaped to first engage the cap edge 32, and then to advance said cap from between the plates 18 and 19, the under surface of said cap being guided by said plates until the cap straightens out. The cap is advanced until the neck 33 thereof is stopped and aligned by its engagement with the wall 34 of the cap support, with the edge 48 of the slide, with the edge 32 in engagement with the wall 31, and with the bottom of the cap resting on the projection 29 of the slide. The springs 61 spread apart under the pressure of the cap to permit the cap to pass therebetween.

80 The means for cutting a cork disc from the strip 15 and for inserting said disc into the cap will now be described. Said means includes the cork inserting plunger 37 which is reciprocated at the proper time within the reciprocating hollow cork cutter 49. Said cutter is secured to the block 50 from which extends the shaft 51 supporting the rollers 52 at the ends thereof. A suitable lever as 53, pivoted to the frame of the machine as at 54, is forked as at one end 55, and engages the rollers 52. The other end 56 of the lever is secured to the eccentric rod 57, which is in turn secured to the eccentric strap 58, mounted on the eccentric 59 on the drive shaft 39. It will be seen that rotation of the shaft 39 100 reciprocates the rod 57 and thereby oscillates the lever 53 to reciprocate the cutter 49 at the proper time to perform the cutting operation upon the cork strip which is at that time 105 at rest. Said strip is sheared between the lower end 60 of the outer surface of the cutter and the hardened lining 36 of the die 135. The strip 15 is fed through a suitable groove 63 in said die by means of the cooperating 110 and preferably knurled and intermittently rotating feed rollers 64 and 65, which engage the leading or perforated end of the strip, and pull said strip through the groove 63 and through the machine under tension.

115 Said rollers are driven through the ratchet wheel 66, which drives the coaxially arranged gear 67 and the roller 65, said gear 67 in turn driving the gear 68 arranged coaxially of the roller 64. The ratchet wheel 66 in turn is 120 intermittently rotated by means of the pawl 69, pivoted to the frame as at 70, and carrying intermediate its ends, the pin 71 which enters the cam slot 72 of the oscillatory cam 73, pivoted to the frame as at 74. Oscillation of 125

the cam is effected through the link 75 connected thereto at one end as at 76, and connected at its other end 77 to the crank disc 78, on the shaft 39.

5 The cork strip 15, before being fed to the machine, passes over the coating roller 79 mounted on the gum box 80 as at 81, and is thereby coated with a layer of silicate of soda 82 or other suitable cementitious material supplied to the gum box. A second preferably flanged roller as 83 engages the upper or uncoated surface of the strip, and cooperates with the roller 79 to tension said strip as it is fed into the machine by the rollers 64 and 65.

10 To reciprocate the plunger 37 for the purpose of inserting the cork into the cap, said plunger passes through the block 50 and is thereby supported for sliding movement therein, the upper end of the plunger terminating in a threaded portion 84, suitably supporting the pin 85 on the adjustable pin block 86, which is suitably threaded for that purpose. The lever 87, pivoted to the frame near one end as 88, is bifurcated at its other end 89 to engage the pin 85. To oscillate the lever 87, a link 90 is connected at one end 91 to said lever intermediate the ends of the lever, and is connected at its other end as at 92 to the lever 53.

15 It will be seen that the plunger 37 is given a greater stroke through the connections just described than the cutter 49. Said connections are so designed that the cutter 49 on its downward movement perforates the strip 15 while said strip is at rest, and carries the disc thus cut from the strip downwardly into the opening 35. The plunger, however, during said downward movement of the cutter, moves faster than the cutter and reaches the disc thus cut at about the time that the cutter 49 releases the disc. The plunger 37 then continues to move downwardly, carrying with it the cork disc with its gummed under surface, and presses said disc against the bottom of the cap, accurate adjustment of the stroke of said plunger being obtained by the adjustment of the pin block 86 on the threaded end 84. The cork disc is sufficiently resilient to take up the pressure exerted by the plunger end thereupon during the cork inserting operation, said pressure being sufficient to cement the disc firmly to the cap.

20 Referring now to the escapement for feeding one cap at a time from the cap chute 14 against the aligning stop 30 (Fig. 5), said escapement comprises the cap catch 95, secured to the rod 96 as at 97, and toothed at its extremities 98 and 99. Said catch is pivoted as at 94 to a suitable extension 104 projecting from the chute. A pin 100 at the upper end of the rod 96 confines the spring 101 thereunder and above the projection 102 of the lever 53, said projection having an opening 103 therein for the passage of the

25 rod. It will be seen that as the projection 102 moves downwardly from the position shown in Fig. 4, the spring 101 is released, thereby permitting the rod 96 to fall under its own weight and swinging the catch 95 in a counter-clockwise direction, and withdrawing the tooth 99 from the cap into which it has been previously inserted.

30 Said cap is thereby released and drops downwardly along the chute until halted by the insertion of the tooth 98 into the threaded opening of the cap. On the upward movement of the lever end 102, the catch 95 is again oscillated from the position of Fig. 5 to that of Fig. 4, whereby the cap 15 previously held by the tooth 98 is released and drops down the chute to the position indicated in Fig. 6. The cap may now be forwarded into cork-receiving position by the slide 21 as has been previously described.

35 After the cork has been inserted into the cap by the movement of the cutter 49 and the plunger 37 and after said cutter and plunger have been withdrawn, the slide 21 is reciprocated toward the right, thereby withdrawing the projection 29 from underneath the corked cap and carrying the opening 44 underneath the cap whereby the corked cap is released and drops through the opening into a suitable receptacle or other means provided therefor.

40 It will be seen that I have provided efficient mechanism for automatically coating cork strips, for cutting said strips into discs, and firmly securing the coated discs into caps, and that said means may be operated with comparatively little attention and at comparatively high speed.

45 While I have shown and described certain specific embodiments of my invention, it will be understood that I do not intend to limit myself thereto, but intend to claim my invention as broadly as may be permitted by the state of the prior art and the scope of the appended claims.

50 I claim:

55 1. In a machine for inserting corks into collapsible tube caps, means for coating the under face of a cork strip with cementitious material, intermittently rotatable means for engaging the leading end of said strip for tensioning said strip and for advancing the strip step by step through the machine, means for shearing a cork from said strip and for advancing the sheared cork into cork-inserting position, a cap chute, a stationary cap stop open at the bottom and having an opening communicating with said chute, a slide for engaging the cap and for advancing said cap from the chute into a position wherein the cap engages the wall of the opening and is aligned coaxially of the cork-inserting means, a projection on said slide for supporting the cap in said position, and means for withdrawing said projection preparatory to the ad-

vance of the succeeding cap and thereby removing the bottom support for said cap whereby the corked cap is discharged by gravity from the machine.

5. 2. In a machine for inserting corks into collapsible tube caps, means for intermittently feeding a cork strip, means for coating the under face of said strip with cementitious material during the feeding thereof, means 10 for shearing corks from said strip while the strip is at rest, and for advancing the cork into a cap to cement the cork to the cap, a cap chute, a slide for advancing caps from said chute into coaxial alignment with the cork-inserting means, a stop for aligning the cap, and a support for the bottom of the cap on said slide and movable therewith and supporting the cap during the cork-inserting operation and movable from underneath the 20 cap to discharge the cap by gravity from the machine after the cork has been inserted thereinto.

3. In a machine for inserting corks into collapsible tube caps, a stationary stop for 25 aligning a cap in cork-inserting position, said stop having an opening in the bottom thereof and having an aligning wall forming the side of said opening, and a slide having a cap-engaging wall for engaging and advancing a 30 cap into contact with said aligning wall and having a bottom for supporting the bottom of said cap in the position wherein a cork may be inserted into the cap, means for moving the bottom of said slide out of cap-supporting 35 position and thereby freeing the cap to permit the cap to drop by gravity out of the machine, and means for preventing retrogression of the cap during the withdrawal movement of the slide.

4. In a machine for inserting corks into collapsible tube caps, means for feeding a cap into, and aligning a cap in cork-inserting position including a chute, an aligning stop having an opening therein communicating with said chute, a pair of bent springs in the opening for halting the cap prior to its advance into engagement with the aligning means and reciprocatory means for advancing the cap past the springs and into engagement with the aligning stop and for supporting the cap in cork-inserting position, and movable away from cork-inserting position to permit discharge of the corked cap by gravity, said springs serving further to prevent retrogression of the cap during the withdrawal movement of the cap-supporting and advancing means.

5. In a machine for inserting corks into collapsible tube caps, means for intermittently feeding a cork strip, means for shearing corks from said strip, a cap chute, an escapement cooperating with the chute to permit only a single cap at a time to advance in said chute, means for straightening and advancing a cap delivered in an inclined position by

said chute into cork-inserting position, said means including a reciprocatory slide for supporting the cap during the advance thereof, reciprocatory means arranged concentrically of and inside of the shearing means for inserting the cork sheared from the strip into the cap while the cap is supported by the slide, and means for withdrawing the slide a sufficient distance relatively to the cap to carry the bottom thereof out of engagement with the cap and thereby removing the support for the cap to allow the cap to drop out of the machine.

6. In a machine for inserting corks into collapsible tube caps, a cap chute, means for holding all but one of the caps in the chute against advance therein and for releasing a cap at predetermined intervals a reciprocatory slide for advancing a cap into cork-inserting position, means for aligning the cap in said position a projection on said slide for engaging the bottom of the cap and supporting the cap during the cork-inserting operation, means for inserting a cork coated on its under surface with cementitious material into the cap, and means for moving the slide away from the cap for withdrawing the projection from its engagement with the cap bottom to release the corked cap for discharge from the machine by gravity.

7. In a machine for inserting corks into collapsible tube caps, means for aligning and supporting a cap in cork-inserting position including an apertured reciprocatory slide, a hollow punch for shearing a cork from a coated strip, a plunger reciprocating within the punch for inserting said cork into the cap, and means for moving said slide relatively to the cap to carry the aperture of the slide underneath the cap and thereby to release the cap for discharge by gravity after the cork has been inserted thereinto.

8. In a machine for inserting corks into collapsible tube caps, a cap chute, means for controlling the advance of the caps in said chute and for permitting a single cap at a time to drop to the bottom of said chute in an inclined position including an escapement, means for advancing, aligning and temporarily supporting the cap until a cork has been inserted thereinto, and then releasing the cap to drop out of the machine by gravity, and means for inserting a cork into the cap while it is aligned and supported comprising a hollow punch for shearing a cork from a web, a plunger within the punch, and means for reciprocating said punch and plunger in the same directions but at different speeds.

9. In a machine for inserting corks into collapsible tube caps, a cap chute, an escapement mechanism for discharging a single cap at a time from said chute, a spring-pressed adjustable reciprocatory slide for advancing the cap from the chute into cork-inserting position, and reciprocatory means for cutting

- a cork from a web and for inserting the cork into the cap, said slide being adapted to have part thereof arranged underneath the cap and comprising the sole means for supporting 5 the cap in said position.
10. In a machine for inserting corks into collapsible tube caps, means for shearing a cork from a coated cork strip and for inserting said cork into a cap including a hollow 10 punch, a plunger, and means for reciprocating said punch and plunger as a unit and relatively to each other, and means for aligning and advancing a cap into cork-inserting 15 position and for supporting said cap during the advance thereof and while the cork is being inserted thereinto only, including a reciprocatory slide adapted to be withdrawn from underneath the cap after the cork has been inserted thereinto.
20. 11. In a machine for inserting corks into collapsible tube caps, a pair of intermittently cooperating rolls for engaging the leading end of a cork strip and for intermittently advancing said strip, means for coating the under 25 surface of said strip with cementitious material during the advance thereof, means interposed between the coating means and said rolls for shearing corks from said strip and for inserting the corks into a cap, and 30 means adapted to be inserted underneath a cap during the cork-inserting operation for supporting the cap and then for releasing the cap after the cork has been inserted thereinto to discharge the cap by gravity from the 35 machine.
12. In a machine for inserting corks into collapsible tube caps, a roll for coating the under face of a cork strip, means spaced from the roll for advancing the coated strip, means 40 interposed between the roll and the strip-advancing means for shearing a cork from the strip and for inserting the cork into a cap including a hollow punch, a plunger, and means for reciprocating said punch and 45 plunger as a unit and relatively to each other, and means for advancing a single cap at a time into cork-inserting position, for aligning said cap in said position, and for supporting the cap in said position only, said means being withdrawn from its engagement with the cap after the cork has been inserted thereinto to discharge the corked cap from the machine by gravity.
50. 13. In a machine for inserting corks into collapsible tube caps, means for aligning a cap in cork-inserting position including a member having a wall therein shaped to engage and fit part of the cap, and a slide for advancing the cap against said wall and for 55 supporting the cap temporarily, a hollow cork-cutting reciprocatory member for shearing a cork from a strip and for advancing the cork toward the aligned cap, a plunger reciprocating within the cutting member for 60 inserting the cork into the cap, and means for withdrawing the slide from the cap after the cork has been inserted thereinto to release the cap for discharge from the machine by gravity.
14. In a machine for inserting corks into collapsible tube caps, means for coating a cork strip with cementitious material, means spaced from the coating means for tensioning the strip and for intermittently advancing the strip, means for shearing a cork from the strip and for inserting the cork into a cap including a hollow cork cutter and a plunger reciprocating within the cutter, and means for reciprocating the cutter and the plunger comprising a lever operatively connected to the cutter for reciprocating said cutter through a predetermined distance, a second shorter lever operatively connected to the plunger for reciprocating the plunger through a greater distance whereby the plunger passes through the lower end of the cutter, and a link connecting said levers for causing said levers to operate in unison. 70
15. In a machine for inserting corks into collapsible tube caps, means for shearing a cork from a cork strip and for inserting the cork into a cap including a hollow cork cutter, a plunger reciprocating within the cutter, and of greater length than that of said cutter, and means for reciprocating the cutter and the plunger comprising a lever operatively connected to the cutter for reciprocating said cutter through a predetermined stroke, a second shorter lever operatively connected to the plunger for reciprocating the plunger, means for adjusting the point of operative connection of the shorter lever to the plunger for determining the lowermost limit of the stroke of said plunger, and means for operatively connecting said levers whereby said levers and said plungers move in unison in the same direction but at different speeds. 75
16. In a machine for inserting corks into collapsible tube caps, a stationary die having an opening therein, a hollow reciprocating cutter cooperating with said die for shearing a cork from a cork strip, a plunger reciprocating within the cutter for advancing the sheared cork into a cap, means for aligning, advancing and supporting a cap into a position coaxially of the plunger, a pair of levers operatively connected together for movement in unison and in the same direction, means for operatively connecting one of said levers to the cutter, adjustable means operatively connecting the other lever to the plunger, said levers being so proportioned and pivoted that the lowermost limit of the stroke of the plunger is below the lowermost limit of the stroke of the cutter, and means for withdrawing the cap-supporting means from the cap after the cork has been inserted thereinto by the plunger to 80
- 85

release the cap for discharge from the machine by gravity.

17. In a machine for inserting corks into collapsible tube caps, a hollow punch for 5 shearing corks from a web, a reciprocatory cork-advancing plunger within the punch, a cap chute, an escapement arranged above the bottom of the chute for advancing a single cap at a time from said chute, a stationary 10 die adapted to cooperate with said punch and having an opening communicating with said chute for aligning a cap advanced by said chute in cork-inserting position, and having walls limiting said opening, and a reciprocatory slide for advancing the cap into engagement with said walls and for temporarily supporting said cap.

18. In a machine of the character described, a cap chute, means for releasing a single cap 20 at a time from said chute to permit the released cap to drop to the bottom of the chute, means for advancing the released cap into, and for aligning the cap in, cork-inserting position, and means for inserting a disc into 25 the cap comprising a stationary die having an opening therein for the passage of a cork strip, means reciprocating in the die for shearing a disc from the strip and for pressing the sheared disc into the cap, a pair of 30 oscillatory levers for operating the reciprocating means, and means for operatively connecting the levers for simultaneous movement in the same direction but at different speeds.
